H. SCHAREK.
FLAG ORNAMENT.
FILED DEC. 10, 1921.

UNITED STATES PATENT OFFICE.

HENRY SCHAREK, OF COATESVILLE, PENNSYLVANIA.

FLAG ORNAMENT.

Application filed December 10, 1921. Serial No. 521,560.

To all whom it may concern:

Be it known that I, HENRY SCHAREK, a citizen of the United States of America, residing at Coatesville, in the county of 5 Chester and State of Pennsylvania, have invented certain new and useful Improvements in Flag Ornaments, of which the following is a specification.

This invention relates to certain new and 10 useful improvements in flag ornaments and has particular reference to the provision of an improved means for supporting a plurality of flags in artistic relation whereby the same may be advantageously employed 15 upon the tops of flag staffs to give a pleasing effect or upon the caps of automobile radiators or the like.

The invention aims to provide structure 20 whereby the relationship of the flags may be slightly varied as desired; to provide an efficient, durable and commercial structure, and to mount a series of flags in separate revoluble sets one of which is provided with means affected by a wind current to cause 25 rotation of the same and means being provided for intergearing the sets whereby such rotation of one of the same will cause rotation of the other set.

With the above general objects in view 30 and others that will appear as the nature of the invention is better understood, the present invention consists in the novel form, combination and arrangement of parts hereinafter more fully described in connection 35 with the accompanying drawing and in which like indicating characters refer to like parts throughout the views.

In the drawing,

Figure 1 is an elevational view of a flag 40 ornament constructed in accordance with the present invention and shown operatively attached to the upper end of a flag staff with the flags wholly or partially indicated by dotted lines,

Figure 2 is a fragmentary vertical sectional view taken substantially centrally through the lower portion of Figure 1,

Figure 3 is a horizontal sectional view 50 taken substantially upon line III—III of Figure 2;

Figure 4 is a fragmentary vertical sectional view drawn on a larger scale, and illustrating details of the inner portion of the inclined flag adjusting means, and

Figure 5 is a view similar to Figure 4 55 of the outer portion of such flag adjusting means.

The present invention preferably embodies a base or attaching plate 5 adapted to be secured in any suitable manner upon the 60 upper end of a support 6, which support is shown herein as a main flag staff and the attaching means is shown as screws 7 passing through the plate 5 and entering the flag staff 6. The base plate 5 is provided with 65 a central upright stud 8 having a longitudinal socket and provided with external threads upon the upper end thereof, and a nut 9 is threaded upon the upper end of said stud for a purpose which will presently 70 become apparent.

A central upright flag staff 10 has its lower end revolubly fitted in the socket of the stud 8, while an inverted pan-shaped casing 11 is fixed upon the lower portion of the 75 flag staff 10 in a horizontal position and has a central offset portion 12, the top wall of which rests upon a washer shown in Figure 2 which is disposed upon the lower end of the flag staff 10 and upon 80 the upper end of the nut 9. A broad bearing is thus provided for permitting rotation of the flag staff 10 with slight friction. The vertical annular rim or flange of the casing 11 is provided with internal 85 gear teeth as at 13 and a small idler pinion 14 meshes with these teeth as well as with the teeth of a spur gear 15 fixed upon the stud 8 within the casing 11. The pinion 14 is mounted upon a stub shaft fixed to 90 and projecting upwardly from the top wall of a second casing 16 which is revolubly mounted upon the stud 8 adjacent the gear 15 and which is of preferably hollow construction with concentric inner and outer 95 walls connected by top and bottom walls. The inner and outer walls of the casing 16 are preferably provided with a plurality of alined openings for snug reception of the inner ends of further flag staffs 17 whereby 100 said flag staffs are effectively supported in a horizontal position by said casing 16 and so as to project radially in uniformly spaced relation. The flag staffs 17 may be provided with any suitable means such as hooks 18 105 for attaching flags 19 thereto and each of these flag staffs is provided with an upwardly directed vane 20 extending longi-

tudinally substantially from end to end of the same so that the wind or any other current of air will affect rotation of these flag staffs 17 and the flags 19 carried thereby as well as corresponding rotation of the casing 16 which supports the same. Due to the fact that the hollow stud 8 is stationary as is also the gear 15 which is fixed thereon, the gear 14 will have an orbital path about said gear 15 and will be caused to rotate so as to effect a rotation of casing 11 by engagement with the teeth 13 on the latter. The speed of rotation of the casing 11 may be varied according to the desired ratio of gearing but as shown, the gearing is such as to cause the casing 11 to be rotated at a slower speed than the speed of rotation of the casing 16.

The casing 11 has a multiple flag staff holder fastened on the offset portion 12 thereof embodying a bottom ring portion 21 with set screws 22 for fastening the same on said portion 12 of the casing 11 and having four equally spaced upwardly extending flexible arms 23 rigid therewith, a socket member 24 being rigid with the upper end of each arm 23 and receiving the lower end of a flag staff 25 for supporting the latter in conjunction with a vertically adjustable spider 26 which is slidably mounted on the flag staff 10 above the multiple flag holder. The sockets 24 may be provided with set screws for holding the flag staffs therein as at 27 and said holders or socket members 24 are also provided with inwardly extending and upwardly converging resilient arms 28 which connect to a ring 29 through which the flag staff 10 passes for steadyng said flag staff 10. The ring 29 is also provided with a set screw 30 for securing the flag staff 10 in position and a rectangular frame 31 is revolvably mounted between collars 32 which are fixed upon the upper end portion of the flag staff 10. This frame 31 is of substantially rigid form and adapted to hold a flag 33 in outstretched condition and it is obvious that this flag will be directed by the wind independently of the flag staff 10 so as to extend in the direction of the current of air or in which the wind is blowing. The flags carried by the flag staffs 25 are denoted by the numeral 34 and may obviously be of any desired form. The flag staffs 25 extend upwardly in diverging relation at an inclination and pass through suitable openings provided in the marginal ring 35 of the spider 26 and this spider also includes a plurality of radial spoke members 36 which are attached as at 37 at their inner ends to a collar 38 which is slidably upon the flag staff 10 and which is arranged within a sectional hollow casing 39 through which the flag staff 10 slidably projects, adjusting screws 40 being carried by opposite ends of said casing 39 for securing the latter in ad-

justed position. The casing 39 has radial slots adapted for snug reception of the arms 36 which project therethrough and it is obvious that by adjusting the spider 26 vertically relative to the flag staffs 10 and 25, the degree of inclination of the flag staffs 29 may be varied, the flexible arms 23 and 28 permitting change in the relative positions of the socket members 24 when this is done.

From the foregoing, it will be seen that the flags 34 constitute one set revolvable with and by the flags 19 of the other set by the provision of the vanes 20 on said other set in the presence of the gearing between the two casings 11 and 16.

In operation, the current of air striking the vanes 20 will cause rotation of the flag staffs 17 and the casing 16 together with the idler pinion 14 which will be caused to rotate by engagement of its teeth with the teeth of the gear 15, and as the latter gear is stationary, rotation of the casing 11 in the same direction as the direction of rotation of the casing 16 will be affected by engagement of the teeth of the pinion 14 with the teeth 13 on said casing 11. As the multiple flag holder including the socket members 24 is fixed to the casing 11, the flags 34 and their staffs 25 are caused to rotate with the casing 11 and as the flag holding frame 31 is rotatably carried by the flag staff 10, rotation of the latter will not change the position of the flag 33 in which it is kept by the wind current.

From the foregoing description, it is believed that the construction and operation of the present invention as well as the advantages thereof will be readily understood and appreciated by those skilled in the art.

Minor changes may be made without departing from the spirit and scope of the invention as claimed.

What is claimed as new is:

1. A flag ornament of the class described comprising a main multiple flag holder provided with a plurality of radial flag staffs and mounted for rotation upon a vertical axis, means carried by said flag staffs adapted to be operated by wind current to cause rotation of the same and said flag holder, a second multiple flag holder having means to support a plurality of flag staffs in upwardly diverging relation and rotatably mounted upon a vertical axis, and a reduction gearing between said flag holders whereby rotation of the first named flag holder will cause rotation of the second named flag holder at a reduced speed.

2. A flag ornament of the class described comprising a main multiple flag holder provided with a plurality of radial flag staffs and mounted for rotation upon a vertical axis, means carried by said flag staffs adapted to be operated by wind current to cause rotation of the same and said flag holder, a

second multiple flag holder having means to support a plurality of flag staffs in upwardly diverging relation and rotatably mounted upon a vertical axis, and a reduction 5 gearing between said flag holders whereby rotation of the first named flag holder will cause rotation of the second named flag holder at a reduced speed, said second named flag holder being carried by 10 an inverted pan-shaped casing, and said reduction gearing comprising planetary gearing between said casing and the first named flag holder.

3. A flag ornament of the class described 15 comprising a main multiple flag holder provided with a plurality of radial flag staffs and mounted for rotation upon a vertical axis, means carried by said flag staffs adapted to be operated by wind current to cause 20 rotation of the same and said flag holder, a second multiple flag holder having means to support a plurality of flag staffs in upwardly diverging relation and rotatably mounted upon a vertical axis, a reduction gearing be- 25 tween said flag holders whereby rotation of the first named flag holder will cause rotation of the second named flag holder at a reduced speed, a longitudinally socketed stud provided with means for attaching the same 30 to a support and upon which said first named flag holder is rotably mounted, and a central vertical flag staff rigid with the second named flag holder and rotatably mounted in the socket of said stud.

35 4. A flag ornament of the class described comprising a main multiple flag holder provided with a plurality of radial flag staffs and mounted for rotation upon a vertical axis, means carried by said flag staffs adapted 40 to be operated by wind current to cause rotation of the same and said flag holder, a second multiple flag holder having means to support a plurality of flag staffs in upwardly diverging relation and rotatably mounted 45 upon a vertical axis, a reduction gearing between said flag holders whereby rotation of the first named flag holder will cause rotation of the second named flag holder at a reduced speed, a longitudinally socketed stud 50 provided with means for attaching the same to a support, and upon which said first named flag holder is rotably mounted, and a central vertical flag staff rigid with the second named flag holder and rotatably 55 mounted in the socket of said stud, said second named flag holder comprising a plurality of flag staff receiving socket members flexibly connected, means adjustable upon the central vertical flag staff and engageable 60 with the flag staffs supported by said flexibly connected socket members for varying the inclination of the same upon longitudinally sliding said means on said central vertical flag staff.

65 5. A flag ornament of the class described

comprising a main multiple flag holder provided with a plurality of radial flag staffs and mounted for rotation upon a vertical axis, means carried by said flag staffs adapted to be operated by wind current to cause rotation of the same and said flag holder, a second multiple flag holder having means to support a plurality of flag staffs in upwardly diverging relation and rotatably mounted upon a vertical axis, a reduction 70 gearing between said flag holders whereby rotation of the first named flag holder will cause rotation of the second named flag holder at a reduced speed, a longitudinally socketed stud provided with means for at- 75 taching the same to a support, and upon which said first named flag holder is rotatably mounted, and a central vertical flag staff rigid with the second named flag holder and rotatably mounted in the socket of said stud, said second named flag holder comprising a plurality of flag staff receiving socket members flexibly connected, means adjustable upon the central vertical flag staff and engageable with the flag staffs sup- 80 ported by said flexibly connected socket members for varying the inclination of the same upon longitudinally sliding said means on said central vertical flag staff, said central vertical flag staff having a rigid flag 85 holding frame rotatably mounted upon the upper end thereof.

6. A flag ornament of the class described comprising a main multiple flag holder provided with a plurality of radial flag staffs 100 and mounted for rotation upon a vertical axis, means carried by the flag staffs adapted to be operated by wind current to cause rotation of the same and said flag holder, a second multiple flag holder having means 105 to support a plurality of flag staffs in upwardly diverging relation and rotatably mounted upon a vertical axis, a reduction gearing between said flag holders whereby rotation of the first named flag holder will 110 cause rotation of the second named flag holder at a reduced speed, a longitudinally socketed stud provided with means for attaching the same to a support, and a central vertical flag staff rigid with the second 115 named flag holder and rotatably mounted in the socket of said stud, said second named flag holder comprising a plurality of flag staff receiving socket members flexibly connected, means adjustable upon the central vertical flag staff and engageable with the flag staffs supported by said flexibly connected socket members for varying the inclination of the same upon longitudinally sliding said means on said central vertical 120 flag staff, said means for adjusting the inclination of the flag staffs held by said central members comprising a spider having a marginal ring through which the inclined flag staffs slidably project.

7. A flag ornament of the class described comprising a main multiple flag holder provided with a plurality of radial flag staffs and mounted for rotation upon a vertical axis, means carried by the flag staffs adapted to be operated by wind current to cause rotation of the same, and said flag holder, a second multiple flag holder having means to support a plurality of flag staffs in upwardly diverging relation and rotatably mounted upon a vertical axis, a reduction gearing between said flag holders whereby rotation of the first named flag holder will cause rotation of the second named flag holder at a reduced speed, a longitudinally socketed stud provided with means for attaching the same to a support, and a central vertical flag staff rigid with the second named flag holder and rotatably mounted

in the socket of said stud, said second named flag holder comprising a plurality of flag staffs receiving socket members flexibly connected, means adjustable upon the central vertical flag staff and engageable with the flag staffs supported by said flexibly connected socket members for varying the inclination of the same upon longitudinally sliding said means on said central vertical flag staff, said means for adjusting the inclination of the flag staffs held by said central members comprising a spider having a marginal ring through which the inclined flag staffs slidably project, radial arms attached to said marginal ring and a collar slidable upon the central flag staff and to which said arms are attached at their inner ends.

In testimony whereof I affix my signature.
HENRY SCHAREK.
